[57] ABSTRACT

An electronic control system for internal combustion engines wherein the duration of injection is proportional to a regulating voltage controlled by at least one operative parameter of the engine. To this end an input voltage defined by a succession of sides of a polygon is subjected to a plurality of transistorized circuits adapted to adjust each the slope of one section of the polygon in accordance with a predetermined parameter.

ELECTRONIC CONTROL SYSTEMS FOR INTERNAL COMBUSTION ENGINES

This is a continuation, of application Ser. No. 173,543 filed Aug. 20, 1971, now abandoned.

The present invention has for its object improvement in electronic injection-controlling means for internal combustion engines. In this technical field the most difficult problem to be solved consists in matching the amount of fuel to be injected with the actual requirements of the engine as defined by one or more readily available regulating parameters.

The main parameter which is the most generally resorted to is constituted in the case of engines provided with a controlled ignition, by the pressure in the admission manifold since such engines are always provided with a throttle valve at the input end of the admission manifold while the pressure depends on the speed of rotation on the degree of opening of the throttle valve and consequently on the load.

Now relationship between the pressure and the amount of fuel to be injected is not a linear function and depends also on the rotary speed of the engine.

It has already been proposed to form this function and to provide a non linear control connection between the pressure collector and the member controlling the duration of injection, which member is constituted in all known control systems by a variable resistance for instance, while furthermore a correction depending on the speed of rotation is executed as provided by a tachometric voltage generator or a variable resistance controlled by a centrifugal regulator which is inserted in the circuit.

In addition to the fact that the corrections thus obtained are merely approximative and the parts resorted to are applicable only to the circuits for which they have been designed, said parts show the serious drawback consisting in that the corrections are performed mechanically; consequently it is necessary to take into account the fact that by reason of the friction arising between the different parts and of their wear, the response curve is not steady and cannot be reproduced at successive times.

The present invention has for its object to cut out these drawbacks and it covers improvements in electronic injection controlling means for internal combustion engines, of the type wherein the duration of injection is proportional with a regulating voltage evolved in conformity with at least one operative parameter of the engine. According to the invention an input voltage varying with one operative parameter is transformed into a polygonal curve by means of a circuit including a many transistors as there are sections in the polygon, each of which transistors is connected through its collector with the point connecting two resistances forming a voltage divider, through its base directly or otherwise with the input voltage and through its emitter with the slider of a potentiometric voltage divider through a variable resistance; the position of the slider of said voltage divider defines the operative threshold of the corresponding transistor and, consequently, of the section of the polygon corresponding to said transistor whereas the variable resistance defines the slope of the corresponding polygon section, the regulating voltage being tapped off directly or otherwise at a point between the connecting point between the two resistances forming a voltage divider and the feed voltage.

As a further development of this inventive idea, the invention provides:

- a. that each transistor defining a polygon section is associated with an auxiliary transistor through which it is possible to act on the slope of the corresponding polygon section in a direction opposed to the action of the main transistor, the collector of said auxiliary transistor being connected with the base of the corresponding main transistor while its emitter is connected with the slider of a potentiometric voltage divider through a variable resistance and its base is connected with the point connecting the two resistances of a voltage divider of which resistances one is grounded and the other is connected directly or otherwise with the input voltage and also with the base of the corresponding main transistor through a resistance;
- b. that the input voltage is applied to the base of a pnp or npn transistor inserted through its emitter-collector circuit between ground and a resistance fed by the feed voltage, said pnp or npn transistor serving as an input impedance-matching means adapted to compensate for modifications in temperature in cooperation with the transistor defining the polygon and connected through their bases with the emitter of the impedance matching transistor, said polygon-defining transistors being of the opposite type npn or pnp, the modifications in temperature of the transistors being such that they compensate each other;
- c. that that resistance of the two resistances forming a voltage divider, which is inserted between ground and the collectors of the transistors defining the polygon is a variable resistance whereby the whole polygon may be shifted bodily with reference to the axis of ordinates;
- d. that the point connecting the resistances forming the voltage divider is connected with the base of a first npn or pnp transistor the emitter-collector circuit of which is inserted between the feed voltage and a grounded resistance while a second transistor of the opposite pnp or npn type is connected through its base with the emitter of the first mentioned transistor while its emitter-collector circuit is connected with resistances fed by the feed voltage, said connections producing a compensation for the effects of temperature on the regulating voltage tapped off the collector of the second transistor together with a correction multiplying the regulating voltage, a variable resistance being inserted between the feed voltage and the emitter of the second transistor;
- e. that two or more circuit systems including a number of transistors defining the sections of a polygon and two further transistors transforming the voltage thus obtained into a regulating voltage, are connected with a common resistance connected between ground and the connection between the output transistors of the first and of the second systems, each of which systems is fed with an input voltage which is a linear function of one or more operative parameters of the engine, the regulating voltage being then a combination of the polygons obtained through the different systems;
- f. that a first circuit system including three transistors defining a three-section polygon is controlled by the pressure in the admission pipe while a second circuit system including three transistors defining another polygon is provided, two transistors forming part of the second system being controlled by the operative temperature of the engine, while the cooperating third transistor is controlled by the rotary speed of the engine;

g. that the regulating voltage is applied to an injection-controlling delay circuit including a program-controllable single-junction transistor, a condenser inserted in parallel with the grounded circuit leading to the anode of said single junction transistor, a transistor the collector-emitter circuit of which is also connected in parallel with said grounded circuit while its base receives the pulse starting the injection, a further transistor being connected through its base with the cathode of the single-junction transistor and having its collector-emitter circuit inserted between ground and a resistance fed by the feed voltage, the rectangular injection-controlling signal being tapped off the collector of said transistor, the load on said condenser being applied during the locked period of the single-junction transistor under constant current conditions by means of a generator of current compensated with reference to temperature modifications and including a first pnp or n-p-n transistor the emitter collector of which is inserted between a resistance fed by the feed voltage and the anode of the single-junction transistor, and a second transistor of the opposite n p n or p n p type connected through its collector with the feed voltage, through its emitter with the base of the first transistor and also with a grounded resistance, the base of said second transistor being set at a predetermined voltage by a voltage divider;

h. that the condenser is the injection controlling delay circuit is loaded by the current generator and also during a short period at the beginning of said loading through the collector-emitter circuit of a transistor and a resistance, the base of said transistor being set at a predetermined voltage by a voltage divider in a manner such that said transistor is conductive when the voltage across the terminals of the condenser is lower than the voltage applied to said base and said transistor is locked when the voltage across the terminals of the condenser reaches and rises above that of the base, taking into account the threshold voltage between the base and the emitter;

i. that the condenser in the injection-controlling delay circuit is loaded by the current generator and also during a short period at the beginning of the loading operation through a diode the anode of which is set at a predetermined voltage by a voltage divider so that said diode is conductive as long as the voltage across the terminals of the condenser is lower than the voltage applied to the anode of said diode and is locked when the voltage across said terminals is higher;

j. that a multiplying correction of the duration of injection, depending on the input voltage is obtained by means of a transistor the collector-emitter circuit of which is inserted between the emitter of the feed transistor operating under constant current conditions in the injection-controlling delay circuit and a variable resistance leading to the slider of a potentiometric voltage divider, the base of said transistor being fed by the input voltage while the variable resistance provides means for adjusting the slope of the multiplying correction and the potentiometric voltage divider provides means for adjusting its operative threshold.

By way of example there is illustrated in the accompanying drawings with a view to furthering the understanding of the invention:

in FIG. 1, a simplified diagrammatic view of the injecting system associated with a internal combustion engine;

in FIG. 2 a simplified electronic wiring diagram used for controlling the injection;

FIG. 3 a diagram showing the curve of the voltages obtained vs pressure;

5 FIG. 4 a chart of the different signals produced at different points of the diagram according to FIG. 2; in FIG. 5 a modification of the part P_1 of the circuit according to FIG. 2;

10 FIG. 6 a diagram showing the curve of the voltages obtained vs pressure in the case of the modification of FIG. 5 is used.

Turning now to FIG. 1, it is apparent that the engine 85 is provided with an input manifold 87 and with electromagnetic injectors 20 fitted in said manifold in 15 the case illustrated. It should be remarked that the injectors may be fitted of course as well in the cylinder head in the case of a direct injection. The electromagnetic injectors 20 are fed with fuel by the pipe system 93 inside which it is subjected to pressure by the pump 20 92 sucking the fuel out of the container 91 and delivering it through the filter 89. A hydraulic pressure accumulator 88 is provided as also a pressure regulator 90. The injection controlling signals are released by a member I controlled by the rotation of the engine and 25 producing short pulses applied to the injection-controlling delay system T_c which produces in its turn a rectangular signal to be sent to an amplifier A and thence to a distributor D feeding the injector-controlling signals to the injectors 20 in the sequence required 30 for injection. In the ones illustrated, the duration of injection depends on three parameters, to wit: the pressure in the admission manifold as measured by the pressure gauge 21, the temperature of the engine cooling water measured by the temperature-measuring 35 means 22 and the rotary speed which is proportional to the frequency of the signals produced by the member controlled by the rotary speed of the engine.

Obviously, these parameters are mentioned only by way of example, since other parameters may be relied on in the arrangement disclosed, such as atmospheric pressure, ambient temperature, the position of the gas-throttling valve and the like. In the case illustrated, the pressure measurement obtained by the gauge 21 is applied to an element V_d which produces a voltage 40 which is a linear function of the pressure. The measurement of the temperature of the water obtained at 22 is applied to an element V_t which produces a voltage 45 which is a function of the temperature and lastly the signals produced by the member I are applied to an element V_r which transforms them into a voltage increasing as a linear function of the rotary speed.

The voltage which is a linear function of the pressure is applied to a circuit section P_1 which transforms said voltage into a voltage the curve defining which is 50 formed by three sides of a polygon, the voltage being thus a continuous function of pressure. The voltage which is a function of the temperature of the cooling water and which is produced by the element V_t is applied to a circuit section P_2 which produces a voltage 55 depending on the input voltage fed into it and which is constituted in the present case by a curve comprising two polygon sides of different slopes. Over said voltage, there is superposed a voltage produced by the element E_r under the action of the voltage produced by the 60 element V_r controlled by the rotary speed. Said element E_r is designed in a manner such that the modification provided by the rotary speed is effective only starting from a predetermined threshold and changes no

more beyond a further threshold of rotary speed. The polygon curves produced by the circuit sections P_1 and P_2 are superposed so as to form an output voltage which is fed to the ignition-controlling delay circuit TC whereby the duration of injection is defined. Said duration of injection may be modified by a multiplying effect as provided by an element EC which applies a signal on said controlling delay circuit TC , said element RC being controlled by the voltage produced by the element V_d . It should be remarked that the action of temperature and speed producing the combined signal passing out of the circuit sections P_1 and P_2 forms additive corrections to be incorporated with the main regulating voltage produced by the circuit section P_1 . In contradistinction, the correction introduced by the element EC has a multiplying effect and provides an enrichment for fuel when the engine is under full load.

FIG. 2 is a complete electronic wiring diagram of the injection-controlling means. The element V_d which produces a voltage proportional to the pressure prevailing in the input manifold comprises resistances R_1 , R_2 forming a voltage divider and transistors T_1 , T_2 . These transistors are connected so as to form current generators as provided by connecting the base of the transistor T_1 with a point connecting the resistances R_1 , R_2 while its collector is fed by the feed voltage and its emitter is grounded through the resistance R_1 and is connected with the base of the transistor T_2 , the emitter collector circuit of which is inserted between the feed voltage and the grounded series of resistances R_4 , R_5 and R_6 , the resistance R_6 being variable and connected with the pressure gauge 21. On the collector of the transistor T_2 there appears a voltage V_e which is a linear function of pressure, since the transistors T_1 - T_2 being connected as current generators, any linear shifting of the slider cooperating with the variable resistance R_6 produces a linear modification of the voltage V_e by reason of the actual intensity remaining constant. It should also be remarked that the voltage V_e is compensated as far as temperature is concerned by the particular connections provided for the transistors T_1 , T_2 . As a matter of fact, the transistor T_1 may be of the npn type and the transistor T_2 of the pnp type. Consequently the modifications in the characteristic properties of the transistors produced by modifications in temperature are of opposite directions and therefore compensate each other. The voltage V_e which varies according to a linear law as shown in FIG. 3 with reference to the pressure prevailing in the input manifold is applied to the base of the transistor T_3 forming part of the circuit section P_1 . The transistor T_3 is of the pnp type and plays the part of an input impedance-matching member ensuring compensation for modifications in temperature for the transistors T_4 , T_5 , T_6 which are of the npn type. The correction for temperature operates thus in the same manner as in the case of the V_d circuit. The emitter-collector circuit of the transistor T_3 is inserted between the resistance R_7 connected with the supply of voltage and ground. The emitter of the transistor T_3 is furthermore connected with the base of the transistors T_4 , T_5 and T_6 . The emitters of said transistors are set at a predetermined voltage by connecting said transistors with voltage dividers constituted for T_4 by the resistance R_8 and the potentiometric voltage divider R_{10} , for T_5 by the resistance R_{15} and the potentiometric voltage divider R_{12} and for T_6 by the resistance R_{16} and the potentiometric voltage divider R_{14} . The sliders on said potentiometric voltage dividers R_{10} ,

R_{12} , R_{14} are therefore connected with emitters of the corresponding transistors T_4 , T_5 , T_6 through the variable resistances R_9 , R_{11} , R_{13} respectively. The collectors of said transistors T_4 , T_5 , T_6 are all connected with the point connecting the resistance R_{17} with the variable resistance R_{18} forming with R_{17} a voltage divider, so that said connecting point is subjected to a voltage the value of which varies with the voltage V_e applied on the base of the transistor T_3 . As a matter of fact, for a position of the slider in the potentiometric voltage dividers R_{10} , R_{12} or R_{14} , the transistors T_4 , T_5 , T_6 become conductive for a predetermined threshold and the slope of the voltage obtained then on the collectors is defined by the resistances R_9 , R_{11} , R_{13} . Therefore the voltage at the point connecting the resistances R_{17} and R_{18} appears as constituted by three sections each of which depends on the state of conductivity of a transistor. The first section of the polygon corresponds to the case of only one conductive transistor, and the second section corresponds to the case of two conductive transistors the collector currents on which are added. Obviously, the voltage at the point connecting the resistances R_{17} , R_{18} , does not increase and in fact decreases with the voltage V_e . Consequently, it is necessary to provide matching means adapted to provide a voltage which increases with the input voltage V_e . To this end, the output transistors T_{17} , T_{18} which form again here a current generator as provided by applying to the base of the transistor T_7 the voltage appearing at the point connecting the resistances R_{17} and R_{18} while the collector-emitter circuit of said transistor T_7 is inserted between the supply of voltage and the grounded resistance R_{19} , the emitter of the transistor R_7 being furthermore connected with the base of the transistor T_{18} the emitter-collector circuit of which connects the variable resistance R_{20} connected with the supply of voltage with the grounded resistance R_{21} . Under such conditions, there is obtained on the collector of the transistor T_8 a voltage V_s which assumes the shape of a polygon as illustrated in FIG. 3.

As in the preceding case, the transistors T_7 , T_8 are compensated as to temperature since they are selected of opposite types pnp and npn. The polygon obtained with the arrangement P_1 can be adjusted in different manners. The release of the transistors T_4 , T_5 , T_6 , is defined by the position of the slider on the corresponding voltage dividers R_{10} , R_{12} , R_{14} . The slope of each polygon section is defined by the corresponding variable resistance R_9 , R_{11} , R_{13} . A further possibility of adjustment is afforded by a parallel vertical shifting of the polygon as provided by the variable resistance R_{18} while a multiplying effect is obtainable by the variable resistance R_{20} which allows the slopes of the different sections of the polygon to be modified in an uniform manner.

The value of the temperature of the engine cooling water is introduced by means of the element V_t which produces a voltage depending on said temperature. To this end, there are inserted in series between the supply of voltage and ground, a resistance R_{31} , the diode D , and the resistances R_{32} and R_{33} while the temperature collector constituted in the present case by a thermistance 22 is inserted in parallel with the grounded resistance R_{33} . Under such conditions, there is obtained at the point connecting the resistance R_{31} and the diode D , a voltage which is a function of temperature. This latter voltage is applied to the circuit section P_2 , the connections of which are somewhat similar to those of

P_1 , but provide only two polygon sections. Said polygon sections are produced by the transistors T_{11} and T_{12} , the connections of which are similar to those of the three transistors T_4 , T_5 , T_6 are provided by the potentiometric voltage divider constituted by the resistance R_{30} and the variable resistance R_{29} for the transistor T_{12} and by the potentiometric voltage divider constituted by the resistance R_{27} and the variable resistance R_{26} for the transistor T_{11} . The sliders in the variable resistances R_{26} and R_{29} are connected with the emitters of the corresponding transistors T_{11} and T_{12} through the variable resistances R_{25} and R_{28} respectively. The collectors of the transistors T_{11} and T_{12} are connected with the point connecting the collector of the transistor T_{13} with the resistance R_{24} , which point is also connected with the base of the transistor T_{10} forming part of an output circuit adapted to produce an output voltage in a manner similar to what has been disclosed for the circuit section P_1 . To this end, the collector-emitter circuit of the transistor T_{10} is inserted between the supply of voltage and the grounded resistance R_{23} , the emitter of said transistor T_{10} being furthermore connected with the base of the transistor T_9 , the emitter-collector circuit of which is also inserted between the resistance R_{22} connected with the supply of voltage and the grounded resistance R_{21} which is common for both output stages P_1 and P_2 . There is thus obtained on the interconnected collectors of the transistors T_8 and T_9 an output voltage to which is constituted by the superposition of a voltage defined by the input voltage V_E which is itself a linear function of the pressure in the input manifold and of a voltage defined by the temperature of the engine-cooling water. The compound voltage obtained is furthermore subjected to a correction as required by the rotary speed of the engine and to this end, the entire polygon illustrated in FIG. 3 is shifted bodily, the polygons V_{A_1} and V_{A_3} appearing in said FIG. 3 corresponding to the voltage depending on the speed of rotation. For this purpose, the element Vv is provided which produces a voltage applied to the base of the transistor T_{13} forming part of the element Ev , the value of last-mentioned voltage being a linear function of the rotary speed. Said element Vv includes chiefly the variable resistance R_{42} , a resistance R_{43} , a further resistance R_{44} , a programm-controllable single junction transistor T_{15} , a resistance R_{45} and a resistance R_{46} , said parts being inserted in series between the supply of voltage and ground. The point connecting the resistance R_{44} with the anode of the singlejunction transistor T_{15} is connected with one terminal of a grounded condenser C_2 , the point between the resistances R_{45} and R_{46} is connected with the base of a transistor T_{14} . Furthermore, the control electrode of the single-junction transistor T_{15} is set at a predetermined voltage by the voltage divider constituted by the resistances R_{47} and R_{48} inserted in series between the supply of voltage and ground. There is also provided a connection between the point connecting the resistances R_{45} , R_{46} and the collector of the transistor T_{16} , the emitter of which is grounded. The base of said transistor T_{16} is connected on the one hand with the grounded resistance R_{50} and on the other hand with the pulse generator I through the resistance R_{49} . The above mentioned transistor T_{14} is grounded through its emitter while its collector is fed by the supply of voltage through the resistance R_{41} . Furthermore, the collector of T_{14} is connected with the base of the transistor T_{13} through the resistance R_{40} and with one terminal of the condenser C_1 , the other termi-

nal of which is grounded. The operation of the element Vv is as follows:

Each time a pulse is produced by the member I, the transistor T_{16} becomes conductive and consequently, the condenser C_2 is discharged and the single-junction transistor T_{15} is locked. Immediately, the pulse produced by the member I has disappeared, the transistor T_{16} is locked again and the condenser C_2 begins being reloaded through the resistances R_{42} , R_{43} , R_{44} when the voltage across the terminals of the condenser C_2 has reached a predetermined value with reference to the voltage on the electrode controlling the single-junction transistor T_{15} , the latter becomes suddenly conductive as a consequence of an avalanche effect whereby the transistor T_{14} becomes conductive. This ensures a slow discharge of the other condenser C_1 through the resistance R_{40} and the collector-emitter circuit of the transistor T_{14} . The latter is therefore conductive during the period of conductivity of the programme-controllable single-junction T_{15} , which period of conductivity depends on the capacity of the condenser C_2 and on the value of the resistances R_{42} , R_{43} and R_{44} and also on the voltage applied on the electrode controlling the single-junction transistor T_{15} . The transistor T_{14} is therefore 25 alternately conductive and locked and the condenser C_1 is alternately loaded in accordance with the condition of the transistor T_{14} . Therefore, a voltage series across the terminals of the condenser C_1 , which voltage depends on the ratio between the durations of the 30 locked condition and of the conductive condition of the transistor T_{14} which in its turn depends on the rotary speed of the engine. This voltage is applied on the base of the transistor T_{13} , the collector of which is connected with the base of the transistor T_{10} and the 35 emitter of which is connected with the slider of the potentiometric voltage divider R_{36} through the resistance R_{34} . Said voltage divider R_{36} is inserted in series with the resistance R_{35} between the voltage supply and ground. The resistances R_{36} , R_{35} are inserted between 40 the base of the transistor T_{13} and the voltage supply while the resistance R_{35} connects this same base with ground.

The arrangement thus disclosed forms thus the circuit section Ev which allows the output voltage V_s to 45 vary with the rotary speed, after the manner of an additive correction.

It should be remarked that the diodes D_1 , D_2 , D_3 provide compensation for temperature modifications in 50 a manner well-known per se and act in the stead of the auxiliary transistor arrangement referred to elsewhere. The voltage V_s is applied to the injection-controlling delay system TC through the diode D_3 and the resistance R_{67} . The point connecting said diode D_3 with the resistance R_{67} is furthermore connected with the 55 grounded resistances R_{68} . The delay system TC includes primarily in series between the voltage supply and ground, the resistance R_{66} , the emitter collector circuit of the transistor T_{22} , the programme controllable single-junction transistor T_{23} , the resistance R_{65} and the resistance R_{64} . The condenser C_3 is inserted between ground and the point connecting the anode of the single-junction transistor T_{23} with the collector of the transistor T_{22} . There is provided in parallelism with the condenser C_3 a transistor T_{19} , the emitter of which 60 is grounded and the collector of which is connected through the resistance R_{59} with the anode of the single junction transistor T_{23} . The base of said transistor T_{19} is fed with the injection releasing pulses produced by the 65

member I through the diode D_4 and the resistance R_{57} . Said base of the transistor T_{19} is also connected with the grounded resistance R_{58} . A transistor T_{20} is connected fed through its collector with the voltage supply, through its emitter with the base of the transistor T_{22} , said emitter being grounded through the resistance R_6 while the base of said transistor T_{20} is connected with the middle point of the voltage divider constituted by the resistances R_{60} , R_{61} , inserted between ground and the voltage supply whereby there is obtained with the transistor T_{22} a current generator compensated as to the action of temperature since the two transistors are of opposite types npn and pnp as described for similar pairs of transistors. The injection-controlling signal VTC is tapped off the collector of the transistor T_{21} , which collector is connected with the voltage supply through the resistance T_{63} . The base of said transistor T_{21} is connected with the point connecting the resistances R_{64} and R_{65} and its emitter is grounded. The injection-controlling signal VTC feeds the amplifier A beyond which the rectangular signals are transmitted to the injectors 20 in a sequence corresponding to the desired sequence of injection.

The operation of this arrangement is as follows:

Assuming the single-junction transistor T_{23} is conductive, the transistor T_{21} is also conductive, and consequently, the collector of said transistor T_{21} is substantially at the same voltage as its emitter, that is at ground voltage. Consequently, as long as the transistor T_{21} is conductive, the injection cannot be performed since the voltage TVC is then zero. The voltage V_c across the condenser C_3 is during this period very low and corresponds with the trough current through the single junction transmitter T_{23} . When a pulse is applied by the pulse generator I to the base of the transistor T_{19} through the diode D_4 and the resistance R_{57} , the transistor T_{19} becomes conductive so that the condenser C_3 is entirely discharged through the resistance R_{59} and the collector-emitter circuit of said transistor T_{19} . The single junction transistor T_{23} is then locked as a consequence of the lack of current, and therefore the transistor T_{21} is also locked; the injection controlling signal appears thus on the collector of said transistor T_{21} . The injection controlling signal appearing on said collector is then applied to the amplifier A. As soon as the pulse is no longer applied on the base of the transistor T_{19} , the latter is locked again and the condenser C_3 is loaded again under constant current conditions through the transistor T_{22} . Consequently, the voltage V_c across the condenser C_3 increases according to a linear law up to a value defined by the voltage applied to the electrode controlling the single junction transistor T_{23} which voltage is defined by the output voltage V_e of the circuit sections P_1 , P_2 . When the voltage V_c has reached a predetermined value with reference to the voltage V_e , the single-junction transistor T_{23} is released by an avalanche effect and discharges the condenser C_3 down to a low value corresponding to the trough current passing through said single-junction transistor T_{23} . With the restoration of the conductive condition of the single-junction transistor T_{23} , the transistor T_{21} becomes again conductive and the voltage V_c drops back to a zero value, which corresponds to the end of the injection. Thus the injection period, registers with the period of non-conductivity of the single junction transistor T_{23} , which period is defined by a signal of the beginning of injection applied to the base of the transistor T_{19} and by the release of said single junction

transistor T_{23} obtained by an avalanche effect as soon as the load on the condenser C_3 has reached a predetermined value while the adjustment of said period is provided by an adjustment of the voltage applied to the electrode controlling said single junction transistor T_{23} . It should be remarked that the arrangement described still shows a drawback by reason of the operative threshold of the single junction transistor T_{23} , being equal to about 1.5 volts. Consequently, the ratio between the maximum load of the condenser C_3 and the minimum load of said condenser, as expressed by the voltage V_c would be too small since the maximum voltage is equal to about 7 volts. To remove this drawback, a high speed loading means CR are provided for the condenser C_3 whereby it is possible to begin with the loading under constant current conditions, at threshold voltage. To this end, the base of a transistor T_{18} is set at a predetermined voltage by a voltage divider including the resistances R_{55} and R_{54} and inserted between the feed voltage and ground. The emitter of said transistor R_{18} is connected with the anode of the single-junction transistor T_{23} while its collector is connected with the voltage supply through the resistance R_{56} . By setting the voltage of the base of the transistor T_{18} at a suitable value, the condenser C_3 is reloaded very speedily after each discharge following a pulse applied on the base of the transistor T_{19} , the loading being performed through the resistance R_{56} and the collector-emitter circuit of the transistor T_{18} . When the load voltage T_c of the condenser C_3 has been reached and thereby the voltage on the emitter of the transistor T_{18} has reached a predetermined value with reference to the voltage applied on the base of said transistor, T_{18} , the latter is locked and the condenser C_3 continues being loaded under constant current conditions through the transistor T_{22} . The loading curve is then illustrated by the curve b in FIG. 4. It should be remarked that the transistor T_{18} may be replaced by a diode the anode of which is connected with the point connecting the resistances R_{54} and R_{55} and the cathode of which is connected with the anode of the single-junction transistor T_{23} . The operation is the same as that disclosed hereinabove: the diode remains conductive as long as the voltage applied to its anode lies above the voltage V_c . When said voltage V_c has reached the value of said anode voltage, the diode is no longer conductive and the loading continues as preceding through the transistor T_{22} .

The circuit section EC described hereinafter is intended to increase the richness of injection, that is, it ensures an increase in the duration of injection with a multiplying effect depending on the action arising in the input manifold. This enrichment is intended for an engine operating under maximum power conditions. For this purpose the base of the transistor T_{17} is fed with a voltage V_c which is proportional to the pressure in the admission manifold, the collector of said transistor T_{17} being connected with the emitter of the transistor T_{22} and its emitter being connected with the slider of a potentiometric divider R_{52} through the variable resistance R_{51} . The voltage divider R_{52} is inserted in series with the resistance R_{55} between the supply of voltage and ground, so as to shunt a fraction of the current passing through the resistance R_{56} and to reduce proportionally the current loading the condenser C_3 , whereby the duration of loading and that of the injection is increased. The potentiometer R_{52} provides means for adjusting the starting of the operation of the transistor T_{17} in a manner such that this fraction of

current is shunted only beyond a predetermined threshold, the value of the shunted current which is defined by the voltage V_e being adjusted by the variable resistance R_{51} .

Briefly stated, the circuit section V_d produces a voltage V_e which is a linear function of the pressure in the input manifold of the engine, which voltage is transformed by the circuit section P_1 and P_2 , into a polygon-shaped voltage V_s the shape of which depends furthermore on the temperature of the engine-cooling water. Moreover the bodily shifting of the polygon is controlled by the rotary speed of the engine through the circuit sections V_s and EV , which leads to the obtention of polygon V_{a1} , V_{a2} , V_{a3} , according to the rotary speed as shown in FIG. 3. The polygon-shaped voltage V_s is applied to the injection-controlling circuit section TC and defines the duration of injection as disclosed hereinabove. FIG. 4 shows how said circuit section TC receives the injection-releasing pulse from the pulse generator I (see curve a of FIG. 4). This pulse causes a rectangular pulse V_{tc} to appear at the output of the circuit section TC beyond which it enters the amplifier A . During this time, the voltage across the terminals of the condenser C_3 increases as shown by the curve b of FIG. 4 and defines the duration of injection.

Obviously, the invention is not limited to the invention described and various circuit sections P_1 , P_2 may be designed so as to take into account various operative parameters of the engine and to form voltage polygons the number of sections of which depends on the number of transistors in the circuit section P_1 . Furthermore the voltage V_e may be applied on the bases of the transistors T_4 , T_5 , T_6 either directly or else through an auxiliary transistor as illustrated in FIG. 2. It should also be well understood that the feed voltage is a stabilized voltage. Lastly, the shape of the curves showing the input voltage V_e and of the output voltage V_s may be different from that illustrated in FIG. 3, in which case the input voltage V_e is a linear function of the pressure P while the output voltage V_s shows a polygonal outline the straight sides of which extend with slopes increasing with the pressure P .

Now, in certain cases, the input voltage V_e may be a non-linear function of the pressure P , so that the output voltage V_s has a polygonal outline the sections of which are curvilinear. Similarly, the slopes of the polygon sections may obviously decrease with increasing pressures, without this widening the scope of the invention as defined by the accompanying claims.

FIGS. 5 and 6 illustrate an embodiment providing such a non-linear curve for the input voltage V_e .

Said input voltage V_e which forms a non-linear function of the pressure P in the input manifold is applied to a transforming circuit P' , as provided by feeding with said voltage the base of the transistor T_3 , the emitter of which is connected with the voltage supply through the resistance R_7 and the collector of which is grounded. The emitter of said transistor is furthermore connected with the bases of the transistors T_4 , T_5 through the corresponding resistances R_{71} and R_{74} , the emitters of said transistors T_4 and T_5 being set at a predetermined voltage by means of a voltage divider constituted by the resistance R_8 and the potentiometer R_{10} for the transistor T_4 and the resistance R_{15} and the potentiometer R_{12} for the transistor T_5 . The sliders of said potentiometers R_{10} - R_{12} are connected respectively with said emitters of the transistors T_4 , T_5 through the corresponding variable resistances R_9 - R_{11} . These connections are similar

to those described with reference to FIG. 2 except for the fact that between the main transistors T_4 , T_5 there are provided further transistors T'_4 - T'_5 the emitters of which are also set at a predetermined voltage by means of a voltage divider including the resistance R'_8 , the potentiometer R_{16} and the variable resistance R'_9 for the transistor T'_4 and the resistance R'_{15} , the potentiometer R'_{12} and the variable resistance R'_{11} for the transistor T'_5 . The collectors of said transistors T'_4 - T'_5 are connected with the bases of the corresponding main transistors T_4 , T_5 while their bases are connected with the points connecting the resistances R_{69} - R_{70} and R_{72} - R_{73} respectively, said resistances R_{69} - R_{70} being inserted in series between the emitter of the transistor T_3 and ground. The collectors of the transistors T'_4 - T'_5 are connected as in the case of FIG. 2 with the point connecting the resistance R_{17} with the variable resistance R_{18} , which point is connected furthermore with the base of the transistor T_7 , the collector of which is fed by the supply of voltage while its emitter is grounded through the resistance R_{19} and is connected with the base of the transistor T_8 . The emitter of the latter is connected with the feed supply through the variable resistance R_{20} and its collector is grounded through the resistance R_{21} . The output voltage V_s appears then on the collector of the transistor T_8 and assumes for instance the shape illustrated in FIG. 6. In fact, the transistors T'_4 , T_4 , T'_5 and T_5 produce a current depending on the voltage applied on their bases and on the position selected for the potentiometer sliders R'_8 , R_{10} , R'_{12} , R_{12} and on the adjustment of the variable resistances R'_9 , R_9 , R'_{11} , R_{11} . A suitable adjustment of these different parts ensures the locking of the transistors T'_4 , T'_5 , T_5 while the transistor T_4 remains conductive up to a predetermined value of the input voltage V_e so that the output voltage V_s is given out then by the section a of the polygon. Above said predetermined value of the input voltage V_e , the transistor T'_4 becomes conductive so that the base of the transistor T_4 is subjected to a constant voltage and consequently the output voltage is also constant. This corresponds to a horizontal section b of the polygon. When the input voltage V_e reaches a higher value, the transistor T_8 becomes conductive and consequently the output voltage is given out by the polygon section a' until the transistor T'_5 becomes conductive and acts on the transistor T_{15} . This provides a further constant value of the output voltage V_s as shown by the horizontal section b' . Obviously the shape of the curve is given solely by way of exemplification and according to the adjustment performed on the potentiometers, R'_8 ; R_{10} , R'_{12} , R_{12} and on the variable resistances R'_9 , R_9 , R'_{11} , R_{11} , the starting of the operation of the transistors and the slopes of the curves may be varied as desired with a view to obtaining any type of curves, for instance a polygonal outline the sections a , b , $a'b'$ of which assume slopes which decrease from one section to the next without however reaching horizontality, the example illustrated corresponding thus to a borderline case.

What we claim is:

1. In an electronic system for controlling the duration of injections in a fuel injection internal combustion engine having electrically actuated means for cyclically injecting fuel during discrete time periods in response to successive fuel injection signals of predetermined duration and means for sensing one operating parameter of an engine, said electronic control system being of the type that includes means for generating a regulating

voltage that is a function of such an engine operating parameter and timing means responsive to the regulating voltage and to the operating cycle of such an engine for generating successive fuel injection signals in successive engine cycles, each signal having a duration depending on the amplitude of the regulating voltage, the improvement wherein the means for generating the regulating voltage comprises:

means, adapted for connection to a means for sensing one operating parameter of such an engine, for generating a noncyclical input voltage having a magnitude that is at all times a function of the one engine operating parameter and

means responsive to the magnitude of the input voltage for generating an output voltage having a magnitude that at all times is a predetermined nonlinear function of the input voltage, the curve of the output voltage as a function of the input voltage consisting of a predetermined plurality of curve segments having different average slopes.

2. In an electronic system for controlling the duration of injections in a fuel injection internal combustion engine having electrically actuated means for cyclically injecting fuel during discrete time periods in response to successive fuel injection signals of predetermined duration and means for sensing one operating parameter of an engine, said electronic control system being of the type that includes means for generating a regulating voltage that is a function of such an engine operating parameter and timing means responsive to the regulating voltage and to the operating cycle of such an engine for generating successive fuel injection signals in successive engine cycles, each signal having a duration depending on the amplitude of the regulating voltage, the improvement wherein the means for generating the regulating voltage comprises:

means, adapted for connection to a means for sensing one operating parameter of such an engine, for generating a noncyclical input voltage having a magnitude that is at all times a function of the one engine operating parameter and

a plurality of transistor circuits having their inputs connected to the input voltage and their outputs connected to a common load resistance, each transistor circuit being biased to a different predetermined conduction threshold voltage, for generating an output voltage having a magnitude that at all times is a predetermined nonlinear function of the input voltage, the curve of the output voltage as a function of the input voltage consisting of a plurality of curve segments having different average slopes, the number of segments being equal to the number of transistor amplifiers.

3. The injection control system of claim 2 further comprising:

at least one auxiliary transistor connected in the input circuit of one of the transistor circuits, the auxiliary transistor being biased to a predetermined conduction threshold voltage for opposing the effect of the input voltage upon the output of the associated transistor circuit when the input voltage is above the predetermined threshold voltage of the auxiliary transistor.

4. The injection control system of claim 3 comprising a separate auxiliary transistor associated with each of the plurality of transistor circuits.

5. In an electronic system for controlling the duration of injections in a fuel injection internal combustion

engine having electrically actuated means for cyclically injecting fuel during discrete time periods in response to successive fuel injection signals of predetermined duration and means for sensing one operating parameter of an engine, said electronic control system being of the type that includes means for generating a regulating voltage that is a function of such an engine operating parameter and timing means responsive to the regulating voltage and to the operating cycle of such an engine for generating successive fuel injection signals in successive engine cycles, each signal having a duration depending on the amplitude of the regulating voltage, the improvement wherein the means for generating the regulating voltage comprises:

means, adapted for connection to a means for sensing one operating parameter of such an engine, for generating a noncyclical input voltage having a magnitude that is a function of the one engine operating parameter;

a source of substantially constant voltage; a plurality of main transistors having their collectors connected together through a common load resistance to one terminal of the voltage source and each transistor having its emitter connected through a separate biasing circuit to the other terminal of the voltage source, each biasing circuit being set for a different predetermined conduction threshold voltage on the base of its associated transducer, the input voltage being applied to the bases of the main transistors for generating an output voltage across the load resistance as a nonlinear function of the one operating parameter, the curve of the output voltage as a function of that parameter consisting of a plurality of curve segments having different predetermined average slopes, the number of segments being equal to the number of main transistors.

6. The injection control system of claim 5 wherein each biasing circuit comprises:

a potentiometer connected as a voltage divider across the terminals of the voltage source and a variable resistance having one terminal connected to the movable contact of the potentiometer and the other terminal connected to the emitter of its associated main transistor, whereby adjustment of the movable contact of the potentiometer establishes the predetermined conduction threshold of the associated transistor, and adjustment of the variable resistance establishes the predetermined average slope of the output curve segment corresponding to the associated transistor.

7. The injection control system of claim 5 further comprising:

at least one auxiliary transistor having its collector connected to the base of one of the main transistors and its emitter connected through a biasing circuit to the other terminal of the voltage source, the biasing circuit being set for a predetermined conduction threshold voltage on the base of the auxiliary transistor, and the input voltage being applied through a first resistance to the base of the auxiliary transistor and through a second resistance to the junction between the base of the main transistor and the collector of the auxiliary transistor, whereby the auxiliary transistor opposes the effect of the input voltage on the collector current of the main transistor when the base voltage of the auxiliary transistor is above the predetermined conduc-

tion threshold voltage.

8. The injection control system of claim 5 wherein all of the main transistors are of the same polarity type, the system further comprising:

an emitter-follower circuit having a transistor of opposite polarity type interposed between the input voltage and the bases of the main transistors for serving as an impedance-matching unit and for compensating the effect of temperature variations on the operation of the main transistors. 5

9. The injection control system of claim 5 further comprising:

a variable resistance connected between the junction of the common load resistance and the collectors of the main transistors and the other terminal of the voltage source, whereby adjustment of the variable resistance produces vertical shifting of the output voltage curve. 15

10. The injection control system of claim 5 further comprising:

an emitter-follower, including a transistor of one polarity type having its base connected to the junction between the collectors of the main transistors and the common load resistance and

an output amplifier stage, including a transistor of 20 polarity type opposite to that of the emitter-follower transistor having its base connected to the emitter of the emitter-follower and its emitter and collector connected through first and second resistors, respectively, across the voltage source, the regulating voltage appearing as an inversion of the output voltage curve on the collector of the output transistor, whereby the opposite polarity types of the emitter-follower and output amplifier transistors provide temperature compensation for the 25 regulating voltage. 35

11. The injection control system of claim 5 wherein the first resistor is a variable resistor for providing a multiplying adjustment to the values of the regulating voltage. 40

12. In an electronic system for controlling the duration of injections in a fuel injection internal combustion engine having electrically actuated means for cyclically injecting fuel during discrete time periods in response to successive fuel injection signals of predetermined duration and at least one means for sensing a corresponding number of operating parameters, of an engine, said electronic control system being of the type that includes means for generating a regulating voltage that is a function of at least one such engine operating parameter and means responsive to the regulating voltage and to the operating cycle of such an engine for generating successive fuel injection signals in successive engine cycles, each signal having a duration depending on the amplitude of the regulating voltage, the 45 improvement wherein the means for generating the regulating voltage comprises:

means, adapted for connection to a means for sensing a first operating parameter of such an engine for generating a first noncyclical input voltage having a magnitude that at all times is a function of the first engine operating parameter; 50

means responsive to the magnitude of the first input voltage for generating a first output voltage having a magnitude that at all times is a predetermined nonlinear function of the first input voltage, the curve of the first output voltage as a function of the first input voltage consisting of a first predeter- 55

mined plurality of curve segments having different average slopes;

means, adapted for connection to a means for sensing a second operating parameter of such an engine for generating a second noncyclical input voltage having a magnitude that at all times is a function of the second engine operating parameter;

means responsive to the magnitude of the second input voltage for generating a second output voltage having a magnitude that at all times is a predetermined nonlinear function of the second input voltage, the curve of the second output voltage as a function of the second input voltage consisting of a second predetermined plurality of curve segments having different average slopes; and

means for combining the first and second output voltages to form the regulating voltage. 10

13. The injection control system of claim 12 further comprising:

means, adapted for connection to a means for sensing a third operating parameter of such an engine for generating a third noncyclical input voltage having a magnitude that at all times is a function of the third engine operating parameter; and

means responsive to the magnitude of the third input voltage for modifying the magnitude of the second output voltage as a function of the third operating parameter. 20

14. The injection control system of claim 13 wherein the first engine operating parameter is intake manifold pressure, the second operating parameter is the operative engine temperature, and the third operating parameter is engine speed. 30

15. In an electronic system for controlling the duration of injections in a fuel injection internal combustion engine of the type that includes a pulse generator synchronized with engine rotation for generating short triggering pulses corresponding to each injection period, means for generating a regulating voltage having an amplitude that is a function of at least one engine operating parameter, and means for generating successive fuel injection signals, each signal having a duration depending on the amplitude of the regulating voltage, the improvement wherein the means for generating fuel injection signals comprises:

a source of substantially constant voltage; 40

a programmable unijunction transistor having its cathode connected through a load resistor to the negative terminal of the voltage source and its control electrode connected to the output of the regulating voltage generator;

a constant current generator connected between the anode of the programmable unijunction transistor and the positive terminal of the voltage source;

a capacitor connected between the junction of the constant current generator and anode of the programmable unijunction transistor and the negative terminal of the voltage source;

a first transistor having its base connected to a point between the cathode of the programmable unijunction transistor and the load resistor and its collector-emitter circuit connected in series with a second resistor across the voltage source; and

a second transistor having its collector-emitter circuit connected to the junction between the capacitor and the anode of the programmable unijunction transistor and the negative terminal of the voltage source and its base connected to the output of the

pulse generator for discharging the capacitor and blocking the programmable unijunction transistor in response to each triggering pulse from the pulse generator to initiate a corresponding rectangular injection signal at the collector of the first transistor, the capacitor being recharged at a predetermined rate upon termination of the triggering pulse until the capacitor voltage reaches a value, in relation to the regulating voltage on the control cathode of the programmable unijunction transistor, that triggers the unijunction transistor and terminates the rectangular injection signal.

16. The injection control system of claim 15 further comprising:

a second current generator connected between the positive terminal of the voltage supply and the capacitor for charging the capacitor at an increased rate as long as the voltage across the capacitor is less than a predetermined value.

17. The injection control system of claim 16 wherein the second current generator comprises:

a voltage dividing network connected across the voltage source and
a third transistor having its collector-emitter circuit connected between the positive terminal of the voltage source and the capacitor and its base connected to a point on the voltage divider having a predetermined voltage such that the third transistor will conduct only when the capacitor voltage is less than the difference between the predetermined voltage and the base-emitter threshold voltage of the third transistor.

18. The injection control system of claim 16 wherein the second current generator comprises:

a voltage dividing network connected across the voltage source and

a diode having its cathode connected to the capacitor and its anode connected to a point on the voltage divider having a predetermined voltage, whereby the diode will conduct only when the capacitor voltage is less than the predetermined voltage.

19. The injection control system of claim 15 further comprising:

means for correcting the duration of the injection signals as a direct function of the intake manifold pressure.

20. The injection control system of claim 19 wherein the means for correcting the duration of each injection signal as a function of intake manifold pressure comprises:

means for generating an input voltage that is proportional to the intake manifold pressure;

a fourth transistor having its base connected to the input voltage generator and its collector-emitter circuit connected in series with a biasing circuit between the output of the constant current generator and the negative terminal of the voltage source for shunting a portion of the capacitor charging current from the constant current generator whenever the input voltage is greater than the conduction threshold of the fourth transistor as determined by the biasing circuit.
